United States Patent Office

Des. 230,645

Patented Mar. 5, 1974

230,645

HOLDER FOR LEDGER SHEETS OR THE LIKE

Allen L. Dixon, Portage, Mich., assignor to Master-Craft
Corporation, Kalamazoo, Mich.

Filed Sept. 20, 1971, Ser. No. 182,299

Term of patent 14 years

Int. Cl. D19—03

U.S. Cl. D74—2 C

Fig. 1

Fig. 2

Fig. 3

Fig. 5

FIG. 1 is a top plan view of a holder for ledger sheets or the like showing my new design, same being illustrated with the clamping member in a closed position;

FIG. 2 is an end view as seen from the left of FIG. 1;

FIG. 3 is a side view thereof shown partially broken away for convenience of illustration, the clamping member being illustrated in the closed position;

FIG. 4 is a bottom plan view thereof; and

FIG. 5 is a partial side view similar to FIG. 3 but illustrating the clamping member in an open position.

I claim:

The ornamental design for a holder for ledger sheets or the like, as shown and described.
